PERRY D. FRAZER, OF RIDGEWOOD, NEW JERSEY.

TRANSFER REEL.

1,422,954.

Specification of Letters Patent.

Patented July 18, 1922.

Application filed November 29, 1920. Serial No. 426,901.

To all whom it may concern:

Be it known that I, PERRY D. FRAZER, a citizen of the United States, and resident of Ridgewood, Bergen County, New Jersey, have made a certain new and useful Invention Relating to Transfer Reels, of which the following is a specification, taken in connection with the accompanying drawing, which forms part of the same.

10 This invention relates to transfer reeling devices to facilitate the reeling off of the fish line from the usual fishing reels and the drying of the line thereon if desired and the reel is preferably made with a face plate carrying a plurality of line supporting pins while a cooperating detachable cover plate may carry one or more such pins and preferably have a loose or releasing pin which may be conveniently connected to the winding handle used to turn the reel. After the line has been wound up around these pins and between the two plates the releasing or handle pin may be withdrawn so as to release the tension in the coils of line and 20 allow the cover plate to be detached without undesirable rubbing or injury to the line which is of course important where expensive enameled fishing lines are being handled. The face plate and cover plate may 25 be detachably connected by a connector bearing sleeve passing through and formed with a suitable shaft opening and this connector sleeve may be preliminarily connected to one of the plates and detachably connected to the other plate in any suitable way while its central opening enables it to fit on the shaft on which the reel operates. This shaft may be connected to a suitable bracket preferably having a clamping device to connect it to a table or support and also in many cases be advantageously provided with a pivot on which a revoluble take-off frame or device may be mounted to cooperate with the reel and support the coil of line which 40 is being wound thereon.

45 In the accompanying drawing showing in a somewhat diagrammatic way an illustrative embodiment of this invention.

Fig. 1 is a side elevation of the reeling device parts being shown in section.

50 Fig. 2 is a view showing the bracket and take-off frame assembled for packing or shipping.

55 Fig. 3 is a transverse sectional view of the reel taken substantially on the line ~~3-3~~ of Fig. 1; and

Fig. 4 is an enlarged detail section of the detachable connection shown in Fig. 3.

The reel may as indicated in Figs. 1 and 3 comprise a face plate 1, of sheet metal in which a circumferential series of supporting pins such as 7, 8, 9, 10 may be riveted or otherwise connected. The cooperating cover plate 24 which may also be formed of aluminum or other rigid and preferably light sheet metal is preferably formed with holes to accommodate the ends of the face plate pins such as 7, 8 and this cover plate may have in some cases one or more cover pins such as 11, riveted thereto and having their ends loosely engaging holes in the face plate. It is quite desirable in many cases to have one of the pins on which the line is wound preliminarily released or detached so as to loosen the tension or pressure of the coiled line on these pins before the cover plate is withdrawn and for this purpose the releasing pin 26 may be loosely mounted in the cover plate so that its end can be preliminarily withdrawn from the hole of the face plate, so that this pin can move inward sufficiently to release the tension of the line before the plates are taken apart. It is advantageous to have this releasing pin serve as a support for the winding handle 6, by which the reel will be manually rotated to wind up the line thereon and by forming a suitable enlargement or retaining collar 19 on this releasing handle pin 26, it may be permanently though loosely connected with the cover plate so that the danger of its being lost is minimized.

Any suitable bearing holes or portions may be formed on these reel plates and as indicated in Fig. 3, they may be provided with a bearing sleeve 21 preferably permanently secured to one of the plates such as the face plate 1 and this bearing sleeve may be formed with an axial hole for the shaft 20 on which the reel turns when the line is being wound thereon. This bearing sleeve may also serve as a detachable connection for the reel plates and may be provided with any suitable form of detachable connection for this purpose. A desirable arrangement is shown in Fig. 4 as comprising the spring pressed latch or detent 5 pivoted by the pin 22 in a slot or recess 23 in the end of the connector sleeve and normally forced out in its protruding holding position shown by the light spring 25. This holds the reel plates together in oper-

ative position while it is of course easy to manually depress this spring latch so that when forced into the slot the cover plate may be withdrawn from the reduced end 5 of the bearing sleeve 21, so as to separate these plates when it is desired to take off a reeled up coil of line.

A suitable bracket 2 may have the shaft 20 mounted on its upper end as indicated in 10 Figs. 1 and 2 and may have a clamping device such as the clamping screw 18 at its other end so as to secure the bracket firmly to a table or other support. In some cases also it is desirable to have the bracket 15 formed with a vertical pivot such as 17 connected by the enlarged portion 15 to the bracket so as to form a revoluble support for the journal or sleeve 16 of the take-off frame shown in Fig. 1 as comprising the 20 bottom or plate 3 and the series of supporting loops or wires 12, 13, 14. A coil of fish line or generally similar material may be dropped over these supporting loops and the line wound therefrom onto the fish- 25 ing reel without undesirable twisting or kinking which of course is especially important with high grade and enameled line. By making the bottom plate of this take-off frame of light aluminum of about the 30 same diameter of the reel plates the entire reeling device may be assembled very compactly for packing and shipping and as indicated in Fig. 2 the bracket may be slipped between the supporting loops of the 35 take-off frame so as not to occupy any substantial additional space when the parts are put into a square box or case with the reel plates superimposed on the take-off frame.

This invention has been described in connection with a number of illustrative embodiments, forms, portions, parts, materials, arrangements and methods of manufacture and use, to the details of which disclosure the invention is not of course to be limited, 45 since what is claimed as new and what is desired to be secured by Letters Patent is set forth in the appended claims.

1. The transfer reeling device for fish line, etc., comprising a bracket provided 50 with a clamping screw and with a pivot and bearing support, a take-off frame having a bottom plate and connected journal cooperating with said pivot and supporting loops secured to said bottom plate to form 55 an annular series of guiding supports for a coil of fish line resting on said bottom plate, and a reel comprising cooperating detachable plates, an interposed series of pins including a releasable pin movably mounted 60 with respect to both of said plates and a connector bearing member detachably connecting said plates and cooperating with said bearing support to form a bearing for said reel.

65 2. The transfer reeling device for fish

line, etc., comprising a bracket provided with a pivot and bearing support, a take-off frame having a journal cooperating with said pivot and supporting means to form an annular series of guiding supports for a 70 coil of fish line, and a reel comprising cooperating detachable plates, an interposed annular series of pins and a connector bearing member detachably connecting said plates and cooperating with said bearing 75 support to form a bearing for said reel.

3. The transfer reeling device for fish line, etc., comprising a bracket provided with a pivot and bearing support shaft, a take-off frame having a journal cooperating 80 with said pivot and having supporting means to form guiding supports for a coil of fish line, and a reel comprising cooperating detachable plates, an interposed annular series of pins and a bearing member co- 85 operating with said bearing support to form a bearing for said reel.

4. The take-down transfer reeling device for fish line, etc., comprising a bracket provided with a clamp and with a pivot and 90 shaft, a take-off frame having a bottom plate and connected bearing cooperating with said pivot and wire supporting loops secured to said bottom plate to form guiding supports for a coil of fish line resting 95 on said bottom plate and a reel comprising cooperating detachable plates of substantially the same size as said bottom plate, interposed line supporting pins including a releasable handle pin movably mounted 100 with respect to both of said plates, a bearing sleeve connected to one of said plates and cooperating with said shaft to form a bearing for said reel and means detachably connecting said plates. 105

5. The take-down transfer reeling device for fish line, etc., comprising a bracket provided with a clamp and with a pivot and shaft, a take-off frame having a bottom plate and bearing cooperating with said pivot and closed top guides secured to said bottom plate to form guiding supports for a coil of fish line resting on said bottom plate, and a reel comprising cooperating detachable plates of substantially the same size 115 as said bottom plate, interposed line supporting pins including a releasable pin movably mounted with respect to both of said plates, and a bearing sleeve connected to one of said plates and cooperating with said shaft to form a bearing for said reel. 110

6. The transfer reel for fish line, etc., comprising a face plate and series of pins rigidly and permanently secured thereto and projecting from one side thereof in a circumferential series, a cooperating detachable cover plate having holes to accommodate the ends of the pins in said face plate and having pins permanently secured to said cover plate to complete the circumfer- 125 130

ential series of line supporting pins extending between said cooperating plates, one of such cover plate pins being a releasable handle pin movably connected to said cover 5 plate and provided with a winding handle projecting from the outside of said cover plate, a connector bearing sleeve rigidly connected to said face plate having a reduced end passing through an opening in said 10 cover plate and a spring pressed detachable detent on the projecting end of said connector sleeve to normally hold said cover plate thereon, said connector sleeve being formed with a cylindrical hole to accommodate a 15 supporting shaft on which a reel may be rotated by said winding handle.

7. The transfer reel for fish line, etc., comprising a face plate and series of pins permanently secured thereto and projecting 20 from one side thereof in a circumferential series, a cooperating detachable cover plate having holes to accommodate the ends of the pins in said face plate and having a pin permanently secured to said cover plate to 25 complete the circumferential series of line supporting pins extending between said cooperating plates, one of such cover plate pins being a releasable pin movably connected to said cover plate, a winding handle 30 projecting from the outside of said cover plate, a connector rigidly connected to said face plate having a reduced end passing through an opening in said cover plate and a detachable detent on the projecting end 35 of said connector sleeve to normally hold said cover plate thereon, said connector sleeve being formed with a cylindrical hole to accommodate a supporting shaft on which a reel may be rotated by said winding 40 handle.

8. The transfer reel for fish line, etc., comprising a face plate and series of pins permanently secured thereto and projecting from one side thereof in a circumferential 45 series, a cooperating detachable cover plate having holes to accommodate the ends of the pins in said face plate and having a pin to complete the circumferential series of line supporting pins extending between said cooperating plates, one of such pins being a releasable pin movably connected to said plates and having a connected winding handle 50 projecting from the outside of said cover plate.

9. The take-down transfer reeling device 55 for fish line, etc., comprising a take-off frame having a bottom plate and connected bearing and wire supporting loops secured to said bottom plate to form guiding supports for a coil of fish line resting on said 60 bottom plate, an angular bracket provided at one end with a clamp and with an adjacent pivot adapted to cooperate with said bearing and provided with a shaft adjacent the other end of said bracket, said bracket 65 being adapted to be inserted between said supporting loops so that said bracket can lie adjacent said bottom plate for packing and shipping, and a reel comprising cooperating detachable plates of substantially the same 70 size as said bottom plate, interposed line supporting pins including a releasable handle pin movably mounted with respect to both of said plates, a bearing sleeve connected to one of said plates and cooperating 75 with said shaft to form a bearing for said reel and means detachably connecting said plates, said handle being adapted to rest adjacent said bottom plate when said reel is placed against said loops for packing and 80 shipping.

10. The take-down transfer reeling device for fish line, etc., comprising a take-off frame having a bottom plate and connected bearing and supporting guiding members 85 secured to said bottom plate to form guiding supports for a coil of fish line resting on said bottom plate, a bent bracket provided at one end with a clamp and with an adjacent pivot adapted to cooperate with said 90 bearing and provided with a shaft adjacent the other end of said bracket, said bracket being adapted to be inserted between said supporting guiding members so that said bracket can lie adjacent said bottom plate 95 for packing and shipping, and a reel comprising cooperating detachable plates of substantially the same size as said bottom plate, interposed line supporting pins and a handle, a bearing sleeve connected to one 100 of said plates and cooperating with said shaft to form a bearing for said reel, said handle being adapted to rest adjacent said bottom plate when said reel is placed against said guiding members for packing 105 and shipping.
